MEANS FOR THE HYDRAULIC TRANSMISSION OF POWER

Thomas Watson Paterson, Allerton,
Liverpool, EnglandApplication December 15, 1930, Serial No. 502,333
In Great Britain February 6, 1930

4 Claims. (Cl. 192—60)

This invention relates to the transmission of power wherein variable relative speeds as between power generator and final output are obtained with the combination of toothed gears or rollers and a hydraulic transmitter, so that transmission of an infinitely variable nature or character may be attained without the noises which usually accompany the direct operation of such gears or wheels. Moreover, the apparatus lends itself to compact and robust construction and small power-weight ratio.

The object of the present invention is to provide improvements in hydraulic torque transmitting apparatus of the kind employing pistons or plungers, hereinafter referred to as pistons, accommodated in radially disposed cylinders in a rotor arranged to function within a confining casing provided with a suitable guide track, or the like, to impart reciprocal motion to the pistons. The rotor bearing the pistons may be coupled direct to the power producing unit, and the casing containing the rotor coupled to the power receiving unit, the transmission of such power from the driving to the driven element being dependent upon the hydraulic transmitter interposed between these two elements.

According to the present invention, the rotor, for the purpose of convenience herein coupled to the power producing unit, is provided with a plurality of radially arranged cylinders in which the pistons are reciprocally disposed, whilst the pistons have their peripheral or terminal ends in contact with a toothed or plain-surfaced guide track on the confining casing through the medium of toothed wheels or rollers to ensure free movement of the pistons about the guide track. The guide track itself is preferably arranged as a true ring within the confining casing, but axially offset relative to the axis of the casing, so providing an eccentric track about which the toothed wheels or rollers at the piston ends may rotate to impart reciprocal motion to the pistons when the rotor is set in motion. The pistons are arranged so that each diametrically opposed pair are positively connected; thus reciprocal movement of any one piston within its working cylinder will sympathetically effect corresponding reciprocal movement of its opposed piston, such movement of the pistons being effected solely through their operative engagement with the guide track, i. e. irrespective of the agency of liquid medium.

Further, in order that the pistons in their driving effort against the confining casing may not be rendered inoperative by back thrust, the

wheels or rollers which operate on the guide track of the confining casing are revolvably supported in members movably mounted on the outer ends of the pistons and pivotally connected with the rotor. Consequently, back thrust is absorbed by the pivotal connecting links and their anchoring pins and the pistons may reciprocate freely and truly within their cylinders without being subject to such thrust.

Normally, the cylinders of the rotor are filled to their maximum capacity with oil or other suitable liquid medium, hereinafter referred to as oil, so that a desirable working volume of such oil is maintained between the respective pistons and their confining cylinders, and the cylinders are provided with regulable intercommunicating ports so that transference of the oil from cylinder to cylinder may be freely effected, or such transference restricted within required limits, or if desired, completely obstructed. The confining casing is also normally filled to its maximum capacity with oil to the exclusion of atmospheric air.

If desired, supplemental oil chambers with automatic replenishing means may be used for replacing any oil lost by leakage from the confining chamber after prolonged usage.

I will further describe my invention with the aid of the accompanying sheet of explanatory drawings which illustrate, by way of examples only, several modes of carrying the same into effect.

In said drawings:—

Figs. 1 and 2 are sections—taken at right angles to each other—of one form of apparatus constructed in accordance with the invention.

Fig. 3 is a face view of a valve for manually controlling the apparatus.

Fig. 4 is a view illustrating a modification.

In the several views like characters of reference denote like or equivalent parts wherever they occur.

Referring first to Figs. 1, 2 and 3, 1 indicates a driving shaft and 2 a driven shaft. Disposed in radially-arranged cylinders 3 in a rotor disc 4 secured to shaft 1 are pistons 5 provided at their outer or terminal ends with toothed wheels 6 which mesh with an internally toothed guide track 7 arranged eccentrically to the axis of the respective shafts 1, 2. Said guide track 7 may be in the form of a one or two-piece ring fixed to the inner wall of a two-piece casing or chamber 8 provided at an end of shaft 2.

Normally, rotor disc 4 is filled with oil so as to ensure a sufficient working volume between

pistons 5, whilst casing 8 is also filled with oil in order to prevent leakage of the oil from the working cylinders 3 of the rotor into its confining casing.

- 5 Said pistons 5 are rigidly connected in diametrically opposed pairs by means of connecting rods 9 so that each pair will operate as a single unit. Thus any one piston will, in traversing guide track 7, reciprocate within its cylinder 10 3 and positively effect corresponding reciprocation of its opposed or connecting piston, such movement of the pistons 5 being effected independently of the liquid contained in the rotor disc 4 of the apparatus.
- 15 Each cylinder 3 of rotor disc 4 communicates by way of a port 10 with a central cavity 11 in the disc, and in said cavity there is disposed a plate valve 12 provided with appropriately spaced peripheral or circumferential recesses 13 which 20 are adapted to be moved into and out of register with said intercommunicating cylinder ports 10 through the medium of a pivotal fork or drag link 14, said fork acting through an axially slideable collar 15, a fixed pin or projection 16 on the collar, and an inclined slot or groove 17 in the valve spindle 18 to partially rotate the latter and so the plate valve 12 which places the cylinders 3 in communication with each other, or isolates these cylinders from each other, as the case 25 may be.

- 30 When said peripheral recesses 13 of plate valve 12 are in register or coincidence with the cylinder ports 10, as illustrated in Figs. 1 and 2, the oil contained in the several cylinders 3 is permitted to freely circulate from cylinder to cylinder so that rotor disc 4 and pistons 5 will revolve with shaft 1 without imparting rotary motion to casing 8, the opposed pairs of pistons being merely maintained in operative contact with 35 the guide track 7 of said casing by their connecting rods 9, whilst the oil is continually injected into and ejected from the working cylinders 3 due to the fact that each piston recedes into and proceeds from its cylinder—thereby 40 making one complete reciprocal movement within its cylinder—in travelling once around guide track 7.

- 45 On the other hand, when the recesses 13 of plate valve 12 are moved out of register with the cylinder ports 10 the latter are sealed or closed by the rim portions 19 of the plate valve, and the oil then contained in each cylinder 3 is trapped: further movement of the respective 50 pairs of pistons 5 is thus prevented and the toothed wheels 6 of those pistons projecting somewhat from their cylinders will, in the continued rotation of driving shaft 1 and rotor disc 4, become locked with guide track 7 of casing 8 and so rotate driven shaft 2 solid with shaft 1.
- 55 Now if restriction be imposed to the free passage of the oil from cylinder to cylinder by partial rotation of plate valve 12, retardation of the pistons' reciprocal function is produced, and as the pistons are proceeding rotationally in unit 60 time, retardation of reciprocal movement must result in either one or other of two actions, namely, rotational movement of casing 8 is effected, or driving shaft 1 is retarded in its rotational speed. This will apply throughout the 65 workable range of the apparatus, from the state of free passage of oil between the several cylinders 3, proceeding by controllably small differences of restriction, until there is finally reached a state where total obstruction to oil transfer-

ence from cylinder to cylinder is established, and at this stage positive connection or direct drive between rotor disc 4 and casing 8 is reached, as previously described; the small differences of restriction to free flow of the oil are thereby responsively reflected in relative variations in speed between shafts 1 and 2 at the will of the operator, by actuation of plate valve 12. In short, by a simple regulation of said plate valve, the available area of cylinder ports 10 may be minutely varied at will, and as each minute variation in the available area of the ports causes a slight difference of speed between rotor disc 4 and casing 8, any desired speed ratios—ranging from free movement of the driving element relative to the driven element to positive or direct coupling of these elements—may be selected according to increase or decrease in the size of cylinder ports 10.

90 It will, however, be realized that if the speed of rotation of the power-producing element coupled to the rotor disc 4 is capable of variation, as in the case of an internal combustion engine of a motor road vehicle, an infinitely variable speed ratio within any predetermined or selected 95 range may be obtained with appropriately set cylinder ports 10, by reason of the fact that increase of engine speed is reflected in increase of re-active effort on the part of the oil contained in the rotor disc 4. Under certain conditions, therefore, the manually operable plate valve 12 may be omitted, although it is desirable to employ this valve as a means of slightly varying the setting of cylinder ports 10 to compensate for differences in working conditions, 100 as it will be readily apparent that the viscosity of the oil in rotor disc 4 and so its speed of transference from cylinder to cylinder will be affected by differences in the load and also in the temperature of the apparatus.

105 It is to be noted that as diametrically opposed pistons 5 are attached by means of connecting rods 9 the possibility of independent movement of any one piston within its cylinder 3 relative to its co-acting piston is definitely prevented with the result that leakage of oil past the piston into casing 8 cannot take place since displacement has not occurred. Under such conditions, the oil in the casing and in rotor disc 4 is in a state of equilibrium, providing, of course, casing 8 is maintained filled with oil to its maximum capacity.

110 The toothed wheels 6 which operate on guide track 7 are carried by suitable bearing members 20 which are themselves slidably mounted on 115 the outer ends of the pistons 5 and pivotally connected by metal straps or links 21 to the rotor disc 4. Thus it will be seen that back-thrust imposed by casing 8 on the driving element will be absorbed by said pivotal connecting straps or links 21 and their anchoring pins 22, and the pistons 5 will, therefore, reciprocate freely and truly within their cylinders 3 without being subject to such thrust. Moreover, by so mounting said toothed wheels 6 on the pistons 120, the outer or terminal ends of the pistons need not protrude out of their cylinders when in their extended or projected positions and so efficient working contact is at all times maintained between the adjacent walls of the pistons 125 and cylinders.

130 The rim portion 23 of plate valve 12 is also permanently maintained in abutment with the end flange 24 of driving shaft 1 by the pressure of oil on the face of this valve and so leakage 135

of oil from the central cavity 11 of rotor disc 4 into the valve spindle passage 25 is practically eliminated. Suitable spring rings, may, however, be provided on valve spindle 18 in order to 5 reduce oil loss between the valve spindle and its passage 25.

In addition, there is formed in driving shaft 1 a helical groove or recess 26 which acts as an impeller to return to casing 8 any oil which may 10 find its way between this shaft and its bearing sleeve 27 during differential rotation of rotor and casing, a suitable packing washer 28 and adjusting gland 29 being also fitted on an end of casing 8 to prevent leakage of oil through 15 said sleeve 27 of the casing.

Further, there are formed on casing 8 appropriately spaced receptacles 30 containing supplementary supplies of oil for replacing any oil which may escape from said casing 8 after prolonged usage, the oil being automatically injected through ball-controlled apertures 31—when the apparatus is quiescent—by means of spring-loaded plungers 32.

It is to be understood that various alterations 25 or modifications as are deemed necessary may be made to the apparatus hereinbefore described without departing from the spirit and scope of the invention as defined by the claims, and in this connection it will be seen that Fig. 4 of the accompanying drawings shows a guide track 30 having a plain inner surface 7^a upon which the peripheries of plain rollers or discs may operate such rollers or discs being, of course, mounted on the terminal ends of the pistons 5 in substitution 35 for the toothed wheels 6, as hereinbefore described.

In an alternative mode of construction, shaft 2 may function as a driving shaft and shaft 1 as a driven shaft.

It will also be understood that sympathetic 40 reciprocal motion of the pistons may be effected operatively connecting the same in any other convenient manner other than that already described.

What I claim as my invention and desire to 45 secure by Letters Patent is:—

1. Hydraulic torque transmitting apparatus embodying driving and driven shafts and means for changing their relative speed comprising on 50 one shaft a casing provided with a guide track, and on the other shaft a rotor confined within said casing and provided with radially-disposed cylinders having intercommunicating ports and means to control the passage of liquid through 55 said ports; and pistons accommodated in said rotor cylinders and directly connected in pairs by rigid connecting elements whereby reciprocation of any one piston will sympathetically effect corresponding reciprocal motion of its 60 opposed piston without the agency of liquid in the apparatus; and rollable elements mounted on the outer ends of said pistons and maintained in operative engagement with said guide track of the confining casing by said rigid connecting 65 elements of the pistons, said rollable elements being revolvably supported in bearing members movably mounted on the outer ends of the pis-

tons and pivotally connected with said rotor to permit true reciprocation of said pistons within their respective cylinders.

2. Hydraulic torque transmitting apparatus embodying driving and driven shafts and means for changing their relative speed comprising on one shaft a casing provided with a toothed guide track, and on the other shaft a rotor confined within said casing and provided with radially-disposed cylinders having intercommunicating ports and means to control the passage of liquid through said ports; pistons accommodated in said rotor cylinders and directly connected in pairs by metal rods passing through apertures in the rotor into engagement with the inner ends of opposed pistons; bearing members slidably supported on guides provided on the outer ends of said pistons; toothed wheels revolvably mounted on said movable bearing members and maintained in meshing engagement with said toothed guide track of the confining casing by said direct connecting rods of the pistons; and links pivotally connecting the toothed wheels of individual pistons to adjacent portions of the rotor.

3. Hydraulic torque transmitting apparatus 100 embodying driving and driven shafts and means for changing their relative speed comprising on one shaft a casing provided with a guide track, and on the other shaft a rotor confined within said casing and provided with radially-disposed 105 cylinders having intercommunicating ports and means to control the passage of liquid through said ports; pistons accommodated in said rotor cylinders and directly connected in diametrically-opposed pairs by rigid connecting elements; 110 bearing members movably mounted on the outer ends of said pistons; rollable elements pivotally connected with the rotor and revolvably mounted on said bearing members to operatively connect the pistons with said guide track of the confining 115 casing; and means provided on said confining casing to automatically maintain a maximum working volume of liquid within said casing and the rotor.

4. Hydraulic torque transmitting apparatus 120 embodying driving and driven shafts and means for changing their relative speed comprising on one shaft a casing provided with a guide track, and on the other shaft a rotor confined within said casing and provided with radially-disposed 125 cylinders having intercommunicating ports and means to control the passage of liquid through said ports; pistons accommodated in said rotor cylinders and directly connected in diametrically 130 opposed pairs by rigid connecting elements; bearing members movably mounted on the outer ends of said pistons; rollable elements pivotally connected with the rotor and revolvably mounted on said bearing members to operatively connect the pistons with said guide track of the confining 135 casing; and supplementary liquid receptacles fitted externally of the confining casing and provided with spring-loaded ejecting members to automatically inject such liquid by way of non-return means into the confining casing.
